UNITED STATES PATENT OFFICE.

JOHN T. HAWKINS, OF TAUNTON, MASSACHUSETTS, ASSIGNOR OF TWO-THIRDS TO JOHN L. BROWER, OF NEW YORK, N. Y., AND ALEX. F. BROWN, OF MONT CLAIR, NEW JERSEY.

BUFFER-SPRING FOR PRINTING-MACHINES.

SPECIFICATION forming part of Letters Patent No. 237,975, dated February 22, 1881.

Application filed February 13, 1880.

To all whom it may concern:

Be it known that I, JOHN T. HAWKINS, of 5
Taunton, in the county of Bristol and State of
Massachusetts, have invented a new and use-
ful Improvement in Buffer-Springs for Print-
ing-Presses, which improvement is fully set
forth and illustrated in the following specifi-
cation and accompanying drawings, in which—

Figures 1 and 2, respectively, illustrate a
10 side elevation, partly in section, and a plan of
the lower part of a printing-press, embodying
the improvements constituting the invention
herein described and claimed.

In a large number of the varieties of print-
15 ing-presses having reciprocating type-beds it
is necessary to counteract or overcome the mo-
mentum of the type-bed at each end of its stroke,
and this is generally accomplished by means
20 of springs in some form; but as such presses
are run at varying speeds it becomes necessary
to so adjust these springs, automatically or
otherwise, that the reaction afforded by them
25 may be varied proportionately to said speeds.
Where metallic springs are used for this pur-
pose they generally consist of a series in heli-
cal form, which resist the momentum of the
bed by their compression. With nearly all
30 such springs heretofore used a variation in
their resistance to comport with varying speeds
of the bed has been obtained solely by increas-
ing the initial tension or compressive set of
the springs. In all these types of presses the
35 distance through which the springs may act
upon the bed is limited by the fact that the
normal motion of the bed while the impression
is being taken cannot be interfered with with-
out detriment to the character of the work.
The mechanism, therefore, of such machines
40 is such that the springs are allowed to act upon
the bed only through an arbitrary and constant
distance, and this being the case the bed
always begins to compress the springs at the
same time of its travel for either end. Under
45 the above-mentioned conditions, if the initial
compressive set of the springs be increased
for the purpose of resisting the greater mo-
mentum due to an increased speed of bed, the
springs must react upon the bed more violently

at the commencement of their action than at
slower speeds of the bed, and must also accu- 50
mulate greater resistance up to the end of the
stroke of the bed, equal only to the change
made in their initial tension or compressive
set. The action and effect, therefore, of such
springs at high speeds of bed, when thus 55
arranged, are very different from their action
and effect at low speeds of the same, and the
higher such speeds the greater must be the
departure, under such circumstances, from
the theoretically perfect action of a spring. 60
The action of such springs, in order to be per-
fect and uniform in overcoming the momen-
tum of any such moving body as the recipro-
cating bed of a printing-press at any and all
of its different speeds, should offer practi- 65
cally the same initial resistance, constituting
a "zero of resistance" at the commencement
of the bed's motion, accumulating up to the
necessary maximum at the end of the stroke
of the bed, said maximum spring resistance 70
and the ratio of accumulation of such resist-
ance alone varying with the speed of bed.

The object, therefore, of this invention is to
so adapt and arrange in a printing-press a se-
ries of buffer-springs that their above-men- 75
tioned perfect action may be, as nearly as pos-
sible, obtained practically, the method em-
ployed of adjusting said springs for varied
speeds of the bed of the press effecting no
change in their initial reactive force or zero of 80
resistance, whatever that may be, but varying
the accumulation of that resistance and its
maximum degree for any given speed of bed at
pleasure.

The spring mechanism constituting this in- 85
vention is provided with a divided index arc
or scale, which indicates at sight, without ne-
cessitating any trial adjustments, the points of
adjustment for the said mechanism necessary
to insure its proper reaction in opposition to 90
the momentum of the bed at any desired num-
ber of revolutions of the press or speed of its
bed—an object of great importance to correctly
and quickly discern, not only thereby saving
the pressman's time and much wear and tear 95
of the machinery, if not actual breakage of

parts, but also thereby conducing to easy and less noisy motion of parts and greater precision and excellence of work.

The several parts and their arrangement designed to effect these objects will now be described in connection with the above-mentioned figures of the drawings, and then be specifically set forth in the claims.

In the said figures the invention is shown 10 in two forms of arrangement as applicable to two different styles or varieties of machine. In some printing-presses the type-bed is not supported at the center of its width, except immediately under the impression-cylinder. 15 In such form of press the arrangement of springs shown on the left half of the figures is preferable, in order to prevent any tendency of the spring mechanism to spring or depress the central parts of the bed, the resistance of 20 the spring mechanism other than that in direct line of the travel of the bed being, in this case, in a horizontal direction. In those printing-presses in which the type-bed is supported at one or more points near the center of its 25 width the more simple arrangement of springs shown on the right-hand half of the figures is used, the resistance offered by the springs other than that in direct line of motion of the bed being, in this case, vertically downward. 30 In the drawings the lower part of the frame of the press is designated by the letter A, the base-piece by the letter B, and the type-bed by the letter b.

To the bed b are attached the usual curved 35 shoes S S, which act upon the rollers R R, which latter are pivoted to the free ends of the lever L' in the vertical arrangement on the right of the figures, and to the upper arm, L, of the levers L L' in the horizontal arrangement at the left. In the vertical arrangement 40 at the right the lever L' is pivoted at its lower end in the bracket b', attached to the base-piece B. In the horizontal arrangement at the left the lever consists of the two separate 45 arms L L', united to a connecting body or shaft, x, of cylindrical or other suitable form, and is pivoted in the brackets b' b', attached to the side frame A. The lower arm, L', of the lever L L' in the horizontal and the lever L' in the 50 vertical arrangement contain each a curved slot whose curve corresponds to the arc of a circle struck from the pivotal point P.

The rods r r r' each have placed upon them 55 helical springs h h h. The central rod, r', is pivoted at one end at the point P to any suitable part of the press, and the block T slides freely upon it. Its other end is secured in the block T' by the nut n, the block T' sliding freely upon the outer rods, r r. The said outer 60 rods are secured at one end to the block T, and at the other to the yoke y.

The yoke y is secured at any desired point 65 in the curved slot in the lever L' by means of the bolt and nut N, which bolt serves as a pivot upon which the yoke y oscillates.

Each inner rod, r', at each end of the press

is provided with a stop, c, in order to limit the inward motion of the block T, which also, under this construction, limits the inward position of the lever-arms L on the left and 70 L' on the right, and consequently the position of each of the rollers R R. The inward motion of the levers and their rollers being limited by the contact of the blocks T T, with the stops c c, leaves the levers, when not in 75 action, (the rollers R R not being in contact with the shoes S S,) without any tension being exerted upon them by the springs, and permits of the bolt and nut N, with its attached yoke y, being adjusted in the curved slots of the 80 levers without effort. The initial compression of the springs h h may be varied, if desired, by means of the nuts n. A mark or point upon the yoke y, and a divided curved line laid off on the lever-arms L'—the divisions on which correspond to the required position of the yoke y or bolt and nut N in the 85 curved slot for the required speeds or number of strokes of bed indicated by numbers—serve as a guide to the printer in adjusting 90 for such speeds.

The curved slots in the lever-arms L L' being each an arc of a circle struck from the center of oscillation of the yoke y, the initial compression of the springs remains constant, 95 while the farther from the center of oscillation of the levers L L' the yoke y is secured the more rapid will the accumulation of resistance be in the springs, and vice versa, the springs receiving a varying amount of compression for every position of the yoke y.

I do not limit myself to the use of levers with curved slots therein, as these levers may be made solid, with different methods of securing the pivot-bolt and nut N and yoke y in 105 different positions upon said levers, said bolt and yoke describing an arc of a circle from the pivotal point P. All such devices, therefore, which move in arcs of circles upon said 110 levers are within the principle of this my invention.

Having thus fully described my said improvement and its method of operation as of my invention, I claim—

1. In combination with the reciprocating 115 bed of a printing-press, a series of buffer-springs attached at one end to a pivotal center of oscillation, and at the other end adjustably upon or within an arc or curved slot of a rocking lever, whereby the reaction of said 120 springs is varied proportionately to the speed and momentum of said bed without changing the initial compressive set or tension of said springs, substantially as set forth.

2. In combination with the reciprocating 125 bed of a printing-press, a set of buffer-springs adjustably connected to a rocking lever and provided with a pivotal rod having thereon a stop, c, as described, whereby the inward motion of said lever is limited, while leaving it 130 free from pressure for the purpose of adjustment, substantially as set forth.

3. In combination with the reciprocating bed of a printing-press and buffer-springs, as described, a rocking lever provided with an adjusting arc, whereby, while the initial compressive set or tension of said springs is preserved constant, their reaction is increased or diminished for varying speeds of said bed by their varied adjustment within or upon said arc, substantially as set forth.

JOHN T. HAWKINS.
